UNITED STATES PATENT OFFICE.

GIOSUÈ ROSSI, OF MORRISDALE, PENNSYLVANIA.

RAIL-JOINT.

1,266,718.

Specification of Letters Patent. Patented May 21, 1918.

Application filed October 1, 1917. Serial No. 194,167.

To all whom it may concern:

Be it known that I, GIOSUÈ ROSSI, a subject of the King of Italy, residing at Morrisdale, in the county of Clearfield and State of Pennsylvania, have invented certain new and useful Improvements in Rail-Joints, of which the following is a specification.

The primary object of the present invention is the provision of a ready means for detachably locking together the adjacent ends of railway rails when operatively positioned in longitudinal alinement, the construction being especially serviceable for temporary tracks.

A further object of the device is the provision of a means for operatively securing railway rails together in track formation so that the same may be instantly disconnected when desired, the structure being strong and serviceable and eliminating the use of the usual nuts and bolts.

In the drawings forming a part of this application and in which like designating characters refer to corresponding parts throughout the several views,

Figure 1 is a side elevation of portions of rails provided with the present device and illustrated in their operative arrangement.

Fig. 2 is a view thereof, illustrating the manner of disconnecting the rails,

Fig. 3 is a longitudinal sectional view taken upon line III—III of Fig. 1, and

Fig. 4 is a vertical transverse sectional view taken upon line IV—IV of Fig. 1.

It being understood that the present device is adapted for attaching railway rails together in track formation, the device is herein shown in connection with the adjacent end portions of two rails 10 and 11 each of which is provided with the usual tread portion 12, base flanges 13 and connecting web 14, the free ends of the rails 10 and 11 being positioned in substantially abutting relations when the rails are in operative longitudinal alinement.

The rail 11 has the web 14 thereof, provided with an extension 15, the rail 11 being in other respects unaltered but provided with a bolt 16 permanently arranged transversely of the rail 11 at the point of merging between the tread 12 and web 14 of said rail 11. The bolt 16 is preferably formed of two parts threaded from opposite directions into a socket 17 within the rail 11 and has opposite depending guide lugs 18.

The companion rail 10 has its web 14 en-

larged as at 19 at the free end of the rail with a recess 20 formed therein in the end of the rail 10 adapted for the reception of the extension 15 of the rail 11, the recess being 60 between the head 12 and base 13 of the rail 10 and the extension 15 having a curved lower forward edge 15' for permitting its ready reception within and removal from the said recess 20.

Opposite plates 22 are provided on the enlarged web portion 19 of the rail 10 arranged in parallelism and spaced apart for the reception of the extension 15, while a notch 23 being provided in the upper edge 70 of each plate 22 adapted for fitting beneath the adjacent portion of the bolt 16 when the device is assembled with the plates 22 positioned at opposite sides of the web 14 of the rail 11 and at which time the lugs 75 18 will overlie the outer faces of the plates 22. The lower edges 24 of the plates 22 are slightly beveled for permitting the ready assemblage and disconnecting of the rails 10 and 11 and it will be seen that with 80 the extension 15 of the rail 11 arranged within the recess 20 of the rail 10 and with the plates 22 engaging the bolt 16 of the rail 11 as illustrated in Fig. 1 of the drawing, a serviceable joint for the rails 10 and 85 11 is provided and that the rails are easily and quickly assembled in their operative relations in this manner.

It will be understood that each rail for forming the track will have its opposite 90 ends differently constructed, that is, one end of each rail will be formed as is herein illustrated, in connection with the rail 11, while the other end thereof will be formed as herein shown with respect to the rail 10. 95 By inclining either of the rails 10 or 11 with respect to its companion rail, the said rails may be readily disconnected as best illustrated in Fig. 2 of the drawing. The lugs 18 assist the plates 22 and extension 100 15 in withstanding the strains incident to all traffic conditions. While the device is serviceable for permanent track lines, it is especially adapted for quickly laying temporary lines of track which may be readily 105 shifted when desired.

What I claim as new is:—

1. A detachable connection for rails comprising in combination with ends of companion rails one of the same having a web extension, the other rail having a recess in the free end thereof adapted for the recep-

tion of the said extension, opposite plates carried by the end of the recessed rail adapted for engagement at opposite sides with the web having the extension when the 5 rails are assembled and detachable interengaging means between the said plates and the adjacent rail.

2. A rail joint comprising in combination with the end portions of rails adapted for 10 position in longitudinal alinement, one of the said rails having the web thereof projecting forwardly of the rails, a transverse bolt carried at the point of merging of the web and tread portions of said extension- 15 carried rail, the other rail having its end provided with cooperating means associated with the said extension and bolt.

3. A rail joint comprising in combination with the end portions of rails adapted for 20 position in longitudinal alinement, one of the said rails having the web thereof projecting forwardly of the rails, a transverse bolt carried at the point of merging of the

web and tread portions of said extension-carried rail, the other rail having its end 25 provided with a receiving recess for the said extension and further having an enlarged web portion at its free recessed end, parallel plates carried by the said enlarged web portion provided with notches 30 in their upper edges adapted for receiving the said bolt when the rails are arranged in their assembled position.

4. A device of the class described comprising rails having complementally formed 35 end portions, one of said rails having a transverse socket through the merging point of its head and web, and a two-part bolt secured within the said socket having opposite depending lugs, the said bolt with its 40 lugs adapted for cooperating with the adjacently positioned portion of the companion rail when the device is assembled.

In testimony whereof I affix my signature.

GIOSUÈ ROSSI.
